Des. 229,916

Patented Jan. 15, 1974

229,916

COVERED FOOD SERVING VESSEL

Irwin Schneider, Lincolnwood, Ill., assignor to Imperial Arts Corporation, Chicago, Ill.

Filed July 28, 1971, Ser. No. 167,073

Term of patent 14 years

Int. Cl. D7—01

U.S. Cl. D7—18

FIG.1

FIG.3

FIG. 4

FIG. 5

FIG. 6

FIG. 1 is a top plan view of the covered food serving vessel showing my new design;

FIG. 2 is a bottom plan view of the cover member;

FIG. 3 is a side elevational view of the covered food serving vessel;

FIG. 4 is a top plan view of the base member;

FIG. 5 is a bottom plan view of the base member; and

FIG. 6 is a side elevational view of the base member.

I claim:

The ornamental design for a covered food serving vessel, as shown.
